UNITED STATES PATENT OFFICE.

FRANK M. PETERS, OF NEW YORK, N. Y., AND WARREN H. HUNGERFORD, OF CHICAGO, ILLINOIS; SAID HUNGERFORD ASSIGNOR TO SAID PETERS.

MACHINE FOR APPLYING LABELS, SEALS, AND THE LIKE.

1,380,924.

Specification of Letters Patent. Patented June 7, 1921.

Application filed November 4, 1918. Serial No. 260,998.

To all whom it may concern:

Be it known that we, FRANK M. PETERS, a citizen of the United States, residing at the city of New York, borough of Manhattan, in the county and State of New York, and WARREN H. HUNGERFORD, a citizen of the United States, residing at Chicago, Cook county, in the State of Illinois, have invented certain new and useful Improvements 5 in Machines for Applying Labels, Seals, and the like, of which the following is a full, clear, and exact specification.

Our invention relates to improvements in machines for applying labels, seals and the like to packages, cartons, containers or other objects having a plurality of walls or sides arranged at an angle to each other.

Further said invention relates to improvements in packaging machinery, and the same 20 has for its object more particularly to provide a simple, efficient and reliable machine for sealing cartons and the like having a cover or closing flap.

Further said invention has for its object 25 to provide a machine for securing the hinged cover or flap of a carton to the body or receptacle portion thereof.

Further said invention has for its object 30 to provide a machine for securing the cover or closing flap of a carton by means of a sealing member which partly engages the cover or closing flap adjacent to its edge, and one of the side walls of the carton or receptacle adjacent to its upper edge.

Further said invention has for its object to 35 provide a machine in which the sealing members are supported in an open base receptacle, from which the same are individually withdrawn, and then moistened and conveyed to the package to be sealed, and said sealing member then pressed partly into engagement with the cover or sealing flap of the carton and with the side wall of the carton adjacent to the free edge of said cover or sealing flap.

Other objects will in part be obvious and 45 in part be pointed out hereinafter.

To the attainment of the aforesaid objects and ends our invention consists in the novel 50 details of construction and in the combination, connection and arrangement of parts hereinafter more fully described and then pointed out in the claims.

In the accompanying drawings forming 55 part of this specification wherein like numerals of reference indicate like parts,

Figure 1 is a partial transverse sectional view showing a portion of a carton closing machine with a sealing mechanism, in side elevation, applied thereto, the said sealing mechanism constituting one form or embodiment of our said invention;

Fig. 2 is a partial front elevation of said machine showing the sealing mechanism in end elevation;

Fig. 3 is an enlarged detail back view 65 showing the sealing member;

Fig. 4 is an edge or end view thereof, and

Fig. 5 is a perspective view showing one 70 form of package with a sealing member applied thereto.

In the accompanying drawings we have shown a portion of a machine for closing cartons and the like of the general construction shown, described and claimed in United States Letters Patent No. 1,043,863, 75 dated November 12, 1912 granted to Frank M. Peters and Henry H. Hungerford for Machine for wrapping packages.

In said drawings 10 designates a side or longitudinal frame member, 11 a transverse 80 support, and 12 a longitudinal shaft which is suitably geared to a driving shaft not shown. Upon said longitudinal shaft 12 is fixed a cam disk 14 having similar cam grooves 15 in its opposite faces arranged in 85 reversed relation.

It will be understood that the mechanism shown to the left of the broken vertical line $\alpha-\alpha$ represents one side or half of the machine, and that the counter part thereof is 90 arranged at the other side of and to the right of said line.

Upon the longitudinal frame member 10 and transverse support 11 is arranged a longitudinal guide 16 through which the 95 packages or cartons are fed. The said guide 16 is provided in the outer of its vertical walls with a recess or cut-out portion 17, and upon the upper edges of said guide 16, at each side of said recess 17, are secured 100 the ends of transverse supports 18, upon which is mounted a paste receptacle 19 having arms 20 extending upwardly therefrom in which is revolubly mounted a shaft 21 carrying a distributing roll 22, contacting 105 with a pick-up roll 23 extending into said paste receptacle 19 and mounted upon a shaft 24 having its opposite ends supported in the walls of said paste receptacle 19. 25 denotes a gear fixed upon one end of the 110

distributing roll shaft 21, and meshing with a similar gear 26 fixed upon the corresponding end of the pick-up roll shaft 24.

27 denotes a paste roll mounted upon a shaft 28 having its ends supported in the outer ends of arms 29 whose inner ends are pivotally secured to the sides of the paste receptacle supports 18. The said paste roll 27 contacts with the distributing roll 22, and 10 the shaft 28, upon which it is mounted, is provided at one of its outer ends with a gear 30 adapted to mesh with the gear 25 on the distributing roll shaft 21. To impart motion to the gears 26, 25, 30 and their 15 respective rolls 23, 22 and 27, the shaft 24 of the pick-up roll 23 is provided with a sprocket wheel 31 connected by a chain belt 32 with a sprocket wheel 33 fixed upon a counter-shaft 34 supported in bearings 35 20 depending from the package or carton guide 16. Upon said counter shaft 34 is also fixed a second sprocket wheel 36 connected by a chain belt 37 with a larger sprocket wheel 38 fixed upon the driven shaft 12 of 25 the machine.

39 denotes a link having its upper end pivotally secured to one of the arms 29 supporting the paste roll 27, and its lower end forked and embracing the counter shaft 34. Adjacent to the forked end of said link 30 39 is provided a roller 40 which rides upon the periphery of a cam 41 fixed upon the counter shaft 34 by means of which the paste roll 27 is lowered into engagement 35 with the seals or labels in order to transfer paste thereto from the distributing roll 22.

42 denotes brackets extending outwardly at right angles from the sides of the machine at each side of the recess 17 in the 40 package or carton guide 16. Upon the outer ends of said brackets 42 are provided upwardly extending posts 43 upon which is pivotally and tiltingly mounted a label or seal magazine 44 having a depending portion 45 through which extends an adjustable screw 46 adapted to engage with a stop 47 on one of said brackets 42 to limit the inward and upward movement of said magazine.

50 Upon the upper portion of each of the brackets 42 is provided a frame 48 which extends inwardly and terminates at about the outer wall of the guide 16. Within each of said frames 48 are provided two parallel 55 longitudinal guide slots 49, 50, of which the slot 50 is provided in its upper edge adjacent to its inner end with an angular projection 50^a and in its lower edge with a corresponding recess 50^b.

51 denotes a label or seal carrier comprising a suction box 52 having its lower half perforated and its upper half formed as a movable plate 52^a working upon a horizontal hinge. From the lower rear portion 55 of said suction box 52 extends a hollow pro-

jection 51^a having a nozzle 53 extending therefrom adapted to receive a flexible tube extending from a suitable suction apparatus, not shown.

From the opposite edges of the suction 70 box 52, at about the center thereof, the projection 51^a is provided with trunnions 54 supported in rectangular bearing blocks 55 working in the upper guide slots 49 of the frames 48, and to the rear and below said 75 trunnions 54 are provided studs 55^a working in the lower guide slots 50 in said frames.

56 denotes a rod which has its inner end pivotally secured to the rear of the suction box 52, and its outer end extending through 80 a slot 57 in the upper end of an operating lever 58 having its lower end pivotally secured in a bearing 59 extending outwardly from the side member of the machine frame. In order to render the connection between 85 the suction box 52 and the upper end of said operating lever 58 flexible or yielding a coil spring 60 is disposed upon the rod 56 with its ends bearing against the inner side of said operating lever 58 and the suction box 52. 90

In order to permit of the movable plate 52^a of the suction box 52 being actuated independently thereof said plate 52^a is provided with a link 61 which has its inner end pivotally secured to the rear surface of said movable plate 52^a and its other end extending outwardly between the arms 62 of the suction box 52, and its extreme outer end provided with a slot 63 engaged by a pin 64 on the upper end of the operating lever 58. 95

The operating lever 58 is actuated by means of a lever 15 supported in a bearing 63^a secured upon the front of the machine. The said lever 65 has a forwardly extending portion 65^a provided with a pin 64^a 105 engaging a slot 58^a in the operating lever 58, and at its opposite end said lever 65 is pivotally connected to an arm 66 having its rear end bifurcated and embracing the driven shaft 12, and provided adjacent to 110 its bifurcated end with a roller 67 working in the cam groove 15 of the cam 14.

The operation of the machine is as follows:—

It will be understood that when the carton 115 closing machine is in operation, the closed, but unsealed cartons 70 are being continuously fed through the guides 16 of the machine. As the inner shaft 12 is constantly rotating the cam 14 thereon will periodically 120 draw the operating lever 58 inward through the medium of the pivoted lever 65, arm 66 and roller 67 thereon which engages the cam groove 15 of the cam 14. As the lever 58 is drawn inwardly the rod 56 moves the label 125 or seal carrier 51 inwardly within the guides 49, 50. As the carrier 51 is moved inwardly and out of engagement with the open base of the label or seal magazine 44 the upper end of said magazine will move slightly up- 130

ward and outward under the influence of the spring 44^a until its movement is arrested by the engagement of the screw 46 with the stop 47. As the carrier 51 and the magazine 44 5 begins to move, said carrier, by the suction produced therein, will withdraw the lower-most label or seal 69 from the magazine 44, and carry the same upon its upper horizontal surface. As it continues its movement the 10 paste roll 27 will be brought down into contact with the label or seal 69 on the carrier and apply paste thereto. As the carrier with its label thereon is advanced the studs 55^a upon said carrier will engage the cam 15 projections 50^a and cause the carrier to assume a vertical position, in which position it is continued to the end of its movement where it causes the lower half of the label or seal 69 to be pressed against the front 20 wall 71 of the carton 70. Immediately thereafter the upper half or hinged plate 52^a will be caused to move inward and downward and assume a horizontal position under the continued inward movement of the lever 25 58 and rod 61, and thereby cause the upper half of the label 69 to be pressed into engagement with the cover 72 of the carton, and seal the same, and complete the operation.

With the continued rotation of the shaft 30 12 the parts will be restored to the initial position shown in full lines at Fig. 1, and the operation first described repeated upon the succeeding carton.

It will of course be understood that the 35 label may be of any desired length or width, and that one or more, as desired, may be applied to the carton to seal the same.

Having thus described our said invention what we claim and desire to secure by Letters Patent is:—

1. A machine of the character described comprising package supporting means, a label magazine, means for transferring a label from said magazine, and means for rendering said label adhesive; said transfer means comprising a support, a foldable member, means for actuating said support to carry the label into engagement with one wall of a package, and means for actuating 45 said foldable member to carry the remainder of said label into engagement with another wall of said package, substantially as specified.

2. A machine of the character described 55 comprising package supporting means, a label holder, means for applying an adhesive to a label, a support, a hinged plate on said support, means for actuating said support and plate jointly to withdraw a label from said holder and bring one part of said label into contact with one wall of said package, and means adapted to actuate said hinged plate at the end of the movement of said support whereby to bring the remainder of 60

said label into engagement with another 65 wall of said package, substantially as specified.

3. A machine of the character described comprising package supporting means, a label holder, a carrier comprising a suction 70 box and a hinged plate, means for actuating said suction box and hinged plate jointly to withdraw a label from said holder and bring one part of said label into contact with one wall of a package, means adapted to actuate 75 said hinged plate independently of said suction box to bring the remainder of said label into contact with another wall of said package, and means for rendering said label adhesive during the transfer thereof from said 80 holder to said package, substantially as specified.

4. A machine of the character described comprising package supporting means, a label holder, means for applying an adhesive 85 to a label, a carrier comprising a suction box and a hinged plate, means for actuating said suction box and hinged plate jointly to withdraw a label from said holder, means for actuating said carrier to cause 90 said suction box to bring one part of said label into contact with one of the walls of said package, and means for actuating said hinged plate independently of said suction box to fold the other part of said label into 95 contact with another wall of said package disposed adjacent to the wall first named, substantially as specified.

5. A machine of the character described comprising package supporting means, a label holder, means for applying adhesive to a label, a carrier comprising a suction box and a plate hinged upon the face of said suction box, a member pivotally secured to said suction box, means for actuating said 105 member to cause said carrier to withdraw a label from said holder and convey the same into contact with one of the walls of said package, a second member pivotally secured to the hinged plate on said carrier having 110 its outer end pivotally connected to the means for actuating said carrier, whereby to actuate said hinged plate independently of said suction box and to fold over the other part of said label and press the same into 115 contact with a movable wall of the package to seal the same, substantially as specified.

6. A machine of the character described comprising a package supporting guide having a recess therein, a label magazine, pasting mechanism for applying an adhesive to a label, guides arranged adjacent to said recess, a carrier mounted to work in said guides, said carrier comprising a suction box having its face divided transversely to form 120 a recessed portion, a hinged plate supported in said recessed portion, an operating lever, a rod having one end pivotally secured to 125

said suction box and its other end slidingly engaged by said operating lever, a spring disposed upon said rod intermediate said suction box and said operating lever, and a link extending through said suction box having its inner end pivotally secured to the hinged plate of said suction box and its outer end slotted and connected to the end of said operating lever, substantially as specified.

10 7. In a machine of the character described, a label carrier comprising a suction box having its face transversely recessed, a plate hinged to said suction box and corresponding in outline with the recessed portion of

15 said suction box, means for jointly actuating said suction box and plate, and means for actuating said hinged plate independently of said suction box after the joint actuation

of said suction box and plate, substantially as specified.
